UNITED STATES PATENT OFFICE.

LOUIS GRANER, OF NEW YORK, N. Y.

LADY'S CIRCULAR-CLOAK.

SPECIFICATION forming part of Letters Patent No. 314,665, dated March 31, 1885.

Application filed April 12, 1884. (No model.)

To all whom it may concern:

Be it known that I, LOUIS GRANER, of New York, county and State of New York, have invented an Improved Lady's Circular-Cloak, 5 of which the following is a full, clear, and exact description, reference being made to the accompanying drawings.

Figures 1 and 2 are inside views of different kinds of my improved lady's circular-cloak. 10 Fig. 3 is a sectional side view of the same; Fig. 4, a diagram of the sleeve-pieces.

Ladies' circulars are heavy, at times fur-lined, cloaks, which at present are usually worn by suspending them from the shoulders 15 of the wearer. Their weight soon renders them oppressive. They must be provided with openings for the hands and arms, through which the air reaches the upper part of the body, chilling the same.

20 My improvement consists in joining the circular-cloak by the upright back-seam to an inner jacket, which protects the upper part of the body and helps to sustain the weight of the cloak.

25 In the drawings, A represents the circular-cloak. B is a jacket having sleeves C. This jacket is by an upright back-seam, a, joined

and stitched to the inner side of the cloak A. The cloak may either have a single back-seam, as in Fig. 1, or three seams, as in Fig. 2. 30

In order to prevent the upper parts of the sleeves, in case the jacket is made from heavy material, from becoming uncomfortable, the upper part of the entire sleeve C, or at least the upper part of the outer portion, b, of the 35 sleeve may be made of thinner material, as indicated at d in Figs. 3 and 4.

I claim—

1. The circular-cloak A, combined and connected by the upright central back-seam, a, 40 only, with the complete jacket B, having sleeves that are adapted to be worn within the cloak, substantially as herein shown and described.

2. The circular-cloak A, connected by an upright row or rows of stitches with an inner 45 jacket, B, having sleeves C, to be worn on inner side of the cloak, the upper parts, d, of which are made of thinner material than the remainder of the sleeves, substantially as herein shown and described.

LOUIS GRANER.
